UNITED STATES PATENT OFFICE.

GEORGE KLEINE, OF CHICAGO, ILLINOIS.

STEREOPTICON.

No. 810,839.

Specification of Letters Patent.

Patented Jan. 16, 1906.

Application filed September 12, 1904. Serial No. 224,090.

To all whom it may concern:

Be it known that I, GEORGE KLEINE, (whose post-office address is 52 State street,) a citizen of the United States, residing at Chicago, 5 county of Cook, State of Illinois, have invented a certain new and useful Improvement in Stereopticons; and I declare the following to be a full, clear, and exact description of the invention, such as will enable others skilled 10 in the art to which it pertains to make and use the same, reference being had to the accompanying drawings, which form a part of this specification.

My invention relates in general to dissolving-stereopticons and more particularly to 15 means for relatively adjusting the lanterns to bring them into register.

As is well known in the art, a dissolving-stereopticon comprises two or more lanterns 20 adapted to successively or simultaneously project views upon the same spot of a curtain. The lanterns must therefore be relatively adjustable in order that they may register. When, as is usual, the lanterns are arranged 25 one above another, they must be relatively longitudinally inclined, in order that the views may be in the same horizontal plane, the degree of such inclination varying according to the distance of the curtain, and the lanterns 30 must also be capable of lateral relative adjustment to insure the views occupying the same vertical plane.

The object of my invention is to provide a dissolving-stereopticon the lanterns composing 35 which may be quickly and easily brought into and retained in register.

A further object of my invention is to provide a dissolving-stereopticon with simple and efficient means for relatively oscillating the 40 lanterns both vertically and horizontally, whereby the views of the lanterns may be readily and accurately registered upon the same spot of an objective curtain.

The embodiment of my invention herein described, generally described, consists in a dissolving-stereopticon having a pair of brackets secured to and projecting above the slide-holder of the lower lantern, a coöperating pair of brackets secured to and depending from 50 the slide-holder of the upper lantern having horizontal slots through their lower ends, screws passing through said slots into engagement with the corresponding brackets on the lower lantern, laterally-projecting ears at 55 each side of the frame which supports the objective lens of the lower lantern having

vertical screw-threaded holes therethrough, right and left screw-threaded rods extending through said holes, beveled gears fixed to the upper ends of said rods, a carrier comprising 60 a horizontal bar above the ends of which the beveled gears are located, and vertical brackets in which is journaled a shaft having beveled gears fixed thereon in mesh with the beveled gears on the vertical rods, a disk for rotating 65 said shaft, a screw-threaded shaft located above the first shaft and rotatively journaled in the brackets of the carrier, and brackets depending from the frame for supporting the lens of the upper lantern through screw-threaded holes in which said screw-threaded 70 shaft passes.

My invention will be more fully described hereinafter with reference to the accompanying drawings, in which the same is illustrated 75 as embodied in a convenient and particular form, and in which—

Figure 1 is a side elevational view; Fig. 2, a front elevational view; Fig. 3, a detail sectional view on line 3 3, Fig. 1; and Fig. 4, a 80 detail sectional view.

The same reference characters are used to designate the same parts in the several figures of the drawings.

Reference characters A' and A² designate 85 the lamp-houses of two lanterns which are used to form a dissolving-stereopticon. B' and B² designate the rings in which are mounted the condensing-lenses of the lanterns.

C' and C² designate the slide-holders of the 90 respective lanterns between which and the lamp-houses the condensing-lenses are removably mounted in any desired manner—such, for instance, as by means of supporting-pins b' and b², which project from the lamp-houses.

C designates a slide in which a picture is removably supported and which in turn is removably held in the holder C' or C² of the respective lanterns. c designates leaf-springs 100 for retaining the slides within the holders.

D' and D² designate collapsible and extensible bellows interposed between the slide-holders and the frames D for supporting the respective objective lenses. The objective 105 lenses are mounted in rings E' and E², each of which is in telescopic engagement with a sleeve E, fixed to and projecting from the corresponding frame D.

Any suitable means, such as indicated at e, 110 may be provided for adjusting the objective lenses to vary the focus.

The lower lantern is provided with supporting-feet d' and d'' beneath the frame D, as clearly shown in Fig. 2, such feet being preferably united by a transverse rod d . Supporting-feet for the lower lanterns are also provided beneath the slide-holder, as indicated at F' in Fig. 1.

Mounted upon the top of the slide-holder C' is a pair of upwardly-projecting brackets H' and H'', such brackets being preferably united at their lower ends by a transverse strap H, through which screws pass into engagement with the top of the slide-holder. A pair of brackets G' and G'' are secured to and depend from the bottom of the slide-holder C' of the upper lantern. The lower ends of the brackets G' and G'' overlie the upper ends of the brackets H' and H'', and are provided with horizontal slots through each of which a screw h passes into engagement with the upper end of the corresponding bracket H' or H''. A transverse rod G preferably extends between the brackets G' and G'' to give the desired strength and rigidity to the structure.

Extending across and secured to the top of the frame D of the lower lantern is a strip O, the ends of which are provided with depending bosses o, having vertical screw-threaded holes therethrough. Right and left screw-threaded shafts O' and O'' extend through the screw-threaded holes in the bosses o. Beveled gears o' and o'' are rigidly secured to the upper ends of the right and left screw-threaded rods O' and O''. Located above the strip O is a carrier P, comprising a bar, through the ends of which the upper ends of the screw-threaded rods loosely pass and above which the beveled gears are located. Brackets P' and P'' extend vertically from the bar P, in which is journaled a shaft R, having fixed thereon beveled gears r' and r'' , in mesh with the beveled gears o' and o''. The shaft R is extended beyond one of the beveled gears thereon and is provided with a disk r, by means of which rotary motion may be imparted to the shaft.

Depending from the frame D, which supports the objective lens of the upper lantern are two brackets S' and S'', the lower ends of which are rigidly united by a cross-bar S, which lies adjacent to the upper surface of the bar P. Brackets S' and S'' are provided with holes through which extends and in which is freely rotatable the shaft R. Alined screw-threaded holes are provided in the brackets S' and S'', through which extends a screw-threaded shaft T, the ends of which are rotatively mounted in the upper ends of the brackets P' and P''. The shaft T is extended beyond one of the supporting-brackets and is provided with a disk t thereon, whereby rotary motion may be imparted to the shaft.

A pair of tubes K' extend longitudinally beneath the upper lantern and are rigidly secured within ears which project inwardly from the brackets G' and G''. Rods L' L'' are se-

cured at corresponding ends to the frame D, which supports the objective lens. The rods L' are in telescopic engagement with the tubes K', by means of which the bellows D' may be extended or contracted to vary the focus. 70 l designates a clamp-screw for locking the corresponding tubes and rods immovably together. A designates a bracket for supporting the lamp-house A' upon the tubes K'. The bracket A is provided with collars surrounding the tubes and through which set-screws extend into contact with the tubes.

A saddle M' is adjustably mounted upon the tubes K' for supporting the burner to which a supply-conduit N extends. m designates a set-screw for locking the saddle to each of the respective tubes K'. 80

The lower lantern is provided with similar telescopic means for uniting the frame of the objective lens to the slide-holder and for supporting the lamp-house and saddle for the burner. L' and K' designate telescopically-united rods and tubes corresponding to the rods and tubes L'' and K'', while M' designates the saddle for supporting the burner within 90 the lamp-house A'.

The manner of using and operation of my improved stereopticon are as follows: When the instrument has been so located and focused that the lower lantern will project a view upon 95 the desired spot of a screen, the upper lantern is adjusted as to its inclination by rotating the rod R by grasping the disk r thereon with the thumb and finger and turning the same in the desired direction. The rotation of the 100 rod R rotates the beveled gears fixed thereon, which in turn rotates the screw-threaded rods O' and O'' through the beveled gears thereon, thereby raising or lowering the bar P with respect to the bar O across the top of the 105 frame D. The shaft R is so rotated that the view projected by the upper lantern occupies the same horizontal plane upon the screen as the view projected by the lower lantern.

In order that the view projected by the 110 upper lantern may occupy the same vertical plane as that projected through the lower lantern, the screw-threaded rod T is rotated, which through the screw-threaded engagement thereof with the brackets S' and S'' oscillates the upper lantern laterally with respect to the lower lantern, such oscillation being permitted by reason of the lateral slots g in the lower ends of the brackets G' and G'', through which extend the screws h.

It is to be understood that while I have illustrated my invention as applied to a dissolving-stereopticon comprising merely two lanterns, yet it is equally well adapted for stereopticons comprising more than two lanterns, it being merely necessary to interpose between each lantern and the one immediately above the same the connecting means shown and described as interposed between the two lanterns herein described. 125 130

While I have described in detail more or less of the construction of the lanterns, yet it will be understood that my invention does not reside in the structure of the lanterns, but is 5 adapted to be applied to a dissolving-stereopticon composed of a plurality of lanterns of any desired construction.

From the foregoing description it will be observed that I have invented an improved 10 dissolving-stereopticon, the views projected by the lanterns of which may be readily brought into register upon a screen and retained in register by simple and efficient means, it being merely necessary to slightly rotate 15 one shaft to adjust the relative inclination of the lanterns and another shaft to adjust one lantern laterally with respect to the other.

While I have described more or less precisely the details of construction, I do not wish 20 to be understood as limiting myself thereto, as I contemplate changes in form, the proportion of parts, and the substitution of equivalents, as circumstances may suggest or render expedient, without departing from the spirit 25 of my invention.

Having now fully described my invention, what I claim as new, and desire to secure by Letters Patent, is—

1. In a dissolving-stereopticon the combination with a plurality of lanterns, of means for pivotally supporting one lantern above another to permit vertical and lateral oscillation, ears projecting laterally from and vertically immovable relatively to the lower lantern, corresponding ears projecting laterally from and vertically immovable relatively to the upper lantern, vertical screw-threaded rods engaging corresponding ears on the upper and lower lanterns, means for simultaneously 35 rotating said rods thereby relatively oscillating the lanterns vertically and means for relatively adjusting the lanterns laterally.

2. In a dissolving-stereopticon the combination with a plurality of lanterns, of means for supporting one lantern above another to permit vertical and lateral oscillation, a bracket projecting upwardly from the lower lantern, a coöperating bracket depending from the upper lantern into the horizontal plane of said 45 upwardly-projecting bracket, means for adjusting said brackets laterally toward and away from each other, and means interposed between the lanterns for relatively vertically oscillating the same.

3. In a dissolving-stereopticon the combination with a plurality of lanterns, of means for supporting one lantern above another to permit vertical and lateral oscillation, a pair of brackets projecting upwardly from the lower lantern a coöperating pair of brackets depending from the upper lantern, and a horizontal screw-threaded rod journaled in the upwardly-projecting brackets and extending through screw-threaded holes in the depending brackets. 55 etc.

4. In a dissolving-stereopticon the combination with a plurality of lanterns, of means for supporting one lantern above another to permit vertical and lateral oscillation, a pair of brackets projecting upwardly above the supporting-frame of the objective lens of the lower lantern, a coöperating pair of brackets depending from the supporting-frame of the objective lens of the upper lantern, and a screw-threaded rod journaled in the upwardly-projecting brackets and extending through screw-threaded holes in the depending brackets. 70

5. In a dissolving-stereopticon the combination with a plurality of lanterns, of brackets depending from the slide-holder of the upper lantern having horizontal slots in their lower ends, coöperating brackets projecting upwardly from the slide-holder of the lower lantern, screws extending through said slots and engaging the upper ends of the lower brackets, and means for oscillating the upper lantern relatively to the lower lantern vertically and laterally upon said screws as fulcrums. 80

6. In a dissolving-stereopticon the combination with a plurality of lanterns, of brackets depending from the slide-holder of the upper lantern having horizontal slots in their lower ends, coöperating brackets projecting upwardly from the slide-holder of the lower lantern, screws extending through said slots into engagement with the upper ends of the lower brackets, a pair of brackets projecting upwardly from the supporting-frame for the objective lenses of the lower lantern, a coöperating pair of brackets depending from the supporting-frame of the objective lens of the upper lantern, a screw-threaded rod journaled in the pair of upwardly-projecting brackets and extending through screw-threaded holes in the pair of depending brackets, and means interposed between the lanterns for relatively vertically oscillating the same. 90

7. In a dissolving-stereopticon the combination with a plurality of lanterns, of brackets depending from the slide-holder of the upper lantern having horizontal slots in their lower ends, coöperating brackets projecting upwardly from the slide-holder of the lower lantern, screws extending through said slots into engagement with the upper ends of the lower brackets, a pair of brackets projecting upwardly from the supporting-frame for the objective lenses of the lower lantern, a coöperating pair of brackets depending from the supporting-frame of the objective lens of the upper lantern, a screw-threaded rod journaled in the pair of upwardly-projecting brackets and extending through screw-threaded holes in the pair of depending brackets, and means interposed between the lower lantern and the brackets projecting upwardly above the objective-lens-supporting frame thereon for raising and lowering said brackets. 100

8. In a dissolving-stereopticon the combination 110

tion with a plurality of lanterns, of brackets depending from the slide-holder of the upper lantern having horizontal slots in the lower ends, coöperating brackets projecting upwardly from the slide-holder of the lower lantern, screws extending through said slots into engagement with the upper ends of the lower brackets, a pair of brackets projecting upwardly from the supporting-frame for the objective lenses of the lower lantern, a coöperating pair of brackets depending from the supporting-frame of the objective lens of the upper lantern, a screw-threaded rod journaled in the pair of upwardly-projecting brackets and extending through screw-threaded holes in the pair of depending brackets, ears having vertical screw-threaded holes projecting laterally from each side of the objective-lens-supporting frames of the lower lantern, right and left screw-threaded rods engaging the holes through said ears, lateral ears carried by the brackets projecting upwardly above the objective-lens-supporting frame through which

said rods rotatably extend, and means for rotating said rods in opposite directions. 25

9. In a dissolving-stereopticon, the combination with a plurality of lanterns, of brackets depending from the slide-holder of the upper lantern having horizontal slots in their lower ends, coöperating brackets projecting upwardly from the slide-holder of the lower lantern, screws extending through the said slots into engagement with the upper ends of the lower brackets, means for oscillating the upper lantern laterally with respect to the lower lantern, and means interposed between the objective-lens-supporting frames of the lanterns for adjusting the same at such point toward and away from each other. 30 35

In testimony whereof I sign this specification in the presence of two witnesses. 40
